CLAIM

The ornamental design for a flexible carrying case for a pager, as shown and described.

DESCRIPTION

FIG. 1 is a front elevational view of a flexible carrying case for a pager showing our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and,

FIG. 7 is a top, front, and right side perspective view thereof. The broken line showing of D-rings is for illustrative purposes only and forms no part of the claimed design.
